INFLATABLE BALL

David Levinson, Chicago, Ill., assignor to Standard Sports Mfg. Co., Chicago, Ill., a corporation of Illinois

Application April 19, 1935, Serial No. 17,194

4 Claims. (Cl. 273—65)

The invention relates generally to inflatable balls and more particularly to an inflatable ball having a valve means positioned adjacent an aperture in the cover, which provides access to the valve means for inflating the bladder.

The general object of the invention is to provide a ball of this type, having the rigid portions of its valve means fully protected on the exterior of the ball by material which is resilient so that the rigid portions will not materially affect the reaction of the ball when struck at that point, and which is shaped to conform to the normal contour of the ball so that the ball will not be distorted.

Another object is to provide a ball in which the valve means is protected from dust and dirt and yet is readily accessible for purposes of inflating or deflating the bladder.

It is also an object to provide an inflatable ball and valve structure therefor which facilitate the inflation and deflation of the bladder.

Other objects and advantages will become apparent from the following description taken in connection with the accompanying drawing, in which:

Fig. 1 is an elevational view of a ball embodying the features of the invention.

Fig. 2 is an enlarged view of a portion of the outer surface of the ball.

Fig. 3 is a sectional view taken on the line 3—3 of Fig. 2 and showing the means for inflating the ball.

Fig. 4 is a view of a part of the structure shown in Fig. 3.

Fig. 5 is a view similar to Fig. 3 but showing a modified form of construction.

Fig. 6 is a view of the inflating means used in connection with the construction shown in Fig. 5.

The invention is embodied in an inflatable ball comprising a cover enclosing a bladder. The preferred embodiment comprises generally a valve structure of the spring-operated type positioned in alignment with an aperture in the cover and secured to the cover. Preferably the valve structure is secured to the cover by a flexible means so that the resiliency of the ball at that point is retained. Protecting the valve structure is a plug secured in the aperture in the cover and so shaped exteriorly as to conform to the contour of the ball. The plug is preferably made of resilient material so that the reaction of the ball to a blow struck at that point is not materially different from the reaction to a blow at any other point. To inflate or deflate the ball, the plug is provided with a small aperture or passage there-

through adapted to receive a tubular inflation needle. The needle is adapted to be inserted through the plug far enough to contact and open the valve, and to be held in that position by the plug.

For purposes of illustration, the invention is shown embodied in a football comprising a cover 10 having an opening for the insertion of a bladder 11, the opening being adapted to be closed after the bladder is inserted. In the present instance, the bladder-insertion opening is shown closed by means such as a lacing 12.

The preferred embodiment of the invention is a ball having access through the cover 10 to the bladder for inflation or deflation thereof at a point spaced from the bladder-insertion opening, and for that purpose, an aperture 13 is provided in the cover. Controlling the inflation and deflation of the bladder is a valve structure 14 of the type which is made of metal and includes a spring-operated valve having a stem 15. The latter has one end positioned within a tubular part 16 at the outer end of the valve structure.

The valve structure, being metallic, is rigid, so that it is undesirable to permit said structure to extend to the exterior of the ball because, if the ball were struck at that point, the reaction of the ball would differ from the reaction, if struck at another portion. For the same reason, it is undesirable to have the valve structure rigidly attached to the cover or to have the valve structure immediately underlie the cover.

One of the chief features of the invention is therefore to attach the valve structure to the cover in a flexible manner. Since it is necessary at times to detach the bladder from the cover, the means for attaching the valve structure to the cover may be such that it may be readily disengaged, in which case the valve structure is removed with the bladder, or said means may permanently attach the valve structure to cover, in which case, the bladder is detachable from the valve structure.

In the present instance, the valve structure is permanently attached to the cover by means of a flexible member preferably made of rubber and comprising a tubular portion 17 and a flange portion 18 at its outer end. The latter is secured against the inner surface of the cover and holds the valve structure in alignment with the aperture 13 in the cover. Preferably the flange portion 18 is secured to the cover by stitching 19, and a cushion 20 of soft leather or the like may, if desired, be placed over the inner face of the flange portion 18 to prevent chafing the bladder, 55

the cushion also being secured by the stitching 19. The tubular portion 17 of the flexible member is preferably molded on and around the valve structure. To attach the bladder thereto, the tubular portion 17 is tapered externally, and the bladder is provided with an inwardly turned stem 21 which is stretched and slipped over the tubular portion 17 to hold the bladder in place and prevent leakage therefrom.

10 As mentioned above, one of the features of the invention is to hold the valve structure spaced from the cover. To this end, the tubular portion 17 of the flexible attaching member extends beyond the outer end of the valve structure so that 15 said outer end is spaced from the cover and is movable relative thereto to a limited extent due to the flexibility of the tubular portion 17. To provide access to the valve structure from the exterior of the ball, the portion 17 provides a 20 depression leading to the outer end of the valve structure, said depression preferably being of the same shape and size as the aperture in the cover.

Another important feature of the invention lies 25 in the manner of inflating and deflating the ball and at the same time protecting the valve structure from dust and dirt. For this purpose, an inflation needle is employed which comprises a body 22 adapted to be attached to a pump or the like and preferably having a spring-operated 30 valve therein. Extending from the body 22 is a tubular needle portion 23 having at its extremity one or more transverse apertures 24. The needle portion 23 is adapted to be inserted into the valve structure to depress the valve stem and open the 35 valve, and then to conduct air thereto from the pump.

To this end, means is provided to hold the needle portion in alignment with the valve stem 15 and at the same time hold the needle portion 40 against longitudinal movement after insertion so that the valve stem will remain in depressed position. Said means is also so constructed that it provides an air-tight seal around the needle portion, protects the valve from dust and dirt, when 45 the needle is removed, and is shaped so that it conforms to the contour of the ball. As shown herein, said means comprises a plug 25 made of resilient material such as rubber and fitting snugly in the aperture 13 and within the tubular 50 portion 17 of the flexible member. To hold the plug 25 in place, a metallic insert 26 is molded in the rubber and extends beyond the inner end of the rubber, as at 27, for threaded engagement with the tubular part 16 of the valve structure. The 55 plug is so proportioned that, when the threaded portion 27 is screwed into the valve structure, the rubber of the plug is drawn into engagement with the end of the valve structure to provide a seal.

60 For the reception of the needle, the plug 25 and its metallic insert 26 have an aperture or passage 28 therethrough. The portion of said passage lying in the insert 26 is of sufficient diameter to provide ample clearance for the needle. 65 But the portion of the passage in the rubber plug is normally somewhat smaller than the needle so that, upon insertion of the latter, the rubber is stretched and thus provides a seal around the needle. Such stretching of the rubber also gives 70 it a tight grip on the needle so that the latter is held against longitudinal movement when inserted and thus holds the valve open. The passage 28 is also so positioned that it holds the needle in alignment with the valve stem 15.

75 Since the plug 26 preferably is to lie flush with

the outer surface of the ball, it is made somewhat longer than desired, and then, after being inserted, the excess length is cut off, so that the outer end face thereof conforms to the contour of the ball. To illustrate this, Fig. 4 shows a plug 5 before insertion and the portion 29 shown in dotted lines, illustrates the portion which is cut off.

In the modified form shown in Figs. 5 and 6, the needle is held in its inserted position by providing a threaded engagement thereof with metal insert 26 in the plug. Thus, the needle is provided with a threaded portion 30 engaging threads cut on the interior of the insert 26, the threaded portion 30 being spaced from the extremity of the 15 needle so that the transverse apertures 24 in the needle will have access to the valve. The rubber portion of the plug may also serve to hold the needle and provide the air-tight seal around the needle. 20

In use, the bladder is inserted into the cover through the bladder-insertion opening, and the stem 21 of the bladder is slipped over the tubular portion 17 of the flexible member securing the valve structure to the cover. In so doing, the 25 stem 21 of the bladder is stretched sufficiently to hold the bladder firmly engaged and to prevent leakage. The ball may then be laced and the plug 25 inserted into the aperture 13 and cut off 30 flush with the cover.

The ball is thus ready for inflation which is accomplished by inserting the needle into the passage 28 far enough to force the valve stem 15 to its open position, the passage 28 holding the needle in alignment with the valve stem. 35 When the needle is so inserted, the stretch of the rubber of the plug holds the needle against longitudinal movement and provides an air-tight seal around the needle. Air may then be pumped through the needle and into the bladder, leakage 40 being prevented by the aforesaid seal, the seating of the plug against the end of the valve structure, and the spring-operated valve in the needle body 22. When the bladder is sufficiently inflated, the needle is merely withdrawn and the 45 valve stem 15 returns to its closed position. For deflating the ball, the needle is similarly inserted and the valve in the needle body 22 is opened to permit the air to escape through the needle.

In the modified form illustrated in Figs. 5 and 6, the needle is inserted by screwing the threads 30 thereon into engagement with the internal threads of the insert 26 of the plug. Such threaded engagement holds the needle in position to force the valve open, while the rubber portion 55 25 of the plug, in conjunction with the threads, provides an air-tight seal around the needle.

From the above description, it will be apparent that I have provided an inflatable ball employing a spring-operated metallic valve which is so attached to the cover that the valve and its attachment will not materially affect the reaction of the ball when struck at the point of attachment. Thus, while the valve structure is metallic 60 and hence non-resilient, it is attached to the cover by a flexible member and held in spaced relation to the cover so that its rigidity does not affect the reaction of the ball. The valve structure is amply protected from dust and dirt by 65 the plug 25 which is made of rubber cut to conform to the contour of the ball. By means of the inflation, the ball is readily inflated or deflated, the needle being yieldably held in proper 70 position for these operations by the grip of the 75

rubber plug or, in the case of the modified form, by the threads 30.

I claim as my invention:

1. In an inflatable ball, the combination of a cover having an aperture therein, a metallic valve structure, a flexible member secured to said cover and having a tubular portion supporting said valve structure with its outer end spaced from the cover, and a plug for protecting the valve structure comprising a threaded portion screwed into the valve structure and a resilient portion shaped to fit snugly in the tubular portion of the flexible member and in said aperture, said plug being apertured to receive a tubular inflation needle.

2. In an inflatable ball having an apertured cover and a metallic valve structure, the combination of a tubular flexible member secured to the cover and supporting said valve structure, and a plug to protect the valve structure comprising a resilient member shaped to fit snugly in the outer end of said flexible member and in the aperture in the cover, and a threaded insert embedded in the inner end of said resilient member and screwed into the valve structure for holding the plug in place, said resilient member

and said insert having a longitudinal passage therethrough to receive a tubular inflation needle.

3. In an inflatable ball, the combination of a cover having an aperture therein, a valve structure, means for securing the valve structure to the cover in alignment with said aperture, and a plug of resilient material secured in said aperture for protecting the valve structure and having a small aperture therethrough to receive a tubular inflation needle to open the valve, said plug having a metallic insert having a screw-threaded engagement with said needle to hold the needle in place.

4. In an inflatable ball, the combination of a cover having an aperture therein, a metallic valve structure, means for securing the valve structure to the cover in alignment with said aperture, and a plug of resilient material positioned in said aperture to protect the valve and having a metallic insert threaded into the valve structure, said plug having an aperture therethrough to receive a tubular inflation needle with the insert internally threaded to cooperate with threads on the needle to hold the needle in place.
